UNITED STATES PATENT OFFICE.

SIMON BRYGIDER, OF NEW YORK, N. Y.

SWIMMING DEVICE.

Application filed August 12, 1927. Serial No. 212,443.

This invention relates to a new and useful device in the nature of a swimming garment, adapted to be worn under a bathing suit, or under the clothing of the wearer, for the purpose of providing buoyancy so as to float the person wearing same, when swimming or learning to swim, and also as a life saving medium.

The object of the invention is to provide a swimming garment embodying certain novel features hereinafter more fully described, claimed and illustrated in the accompanying drawing.

Fig. 1 is a front elevational view of my improved swimming garment.

Fig. 2 is a rear elevational view thereof.

Fig. 3 is a similar view to that shown in Fig. 1 illustrating a modification of my improved garment.

Fig. 4 is an enlarged detail view of the eyelets as embodied in my improved device.

Fig. 5 is a similar view to that shown in Fig. 4 illustrating a further development of the said eyelets.

Fig. 6 is a perspective view illustrating a modification of the said eyelets.

Fig. 7 is a similar view to that shown in Fig. 6 illustrating another modification of the said eyelets.

Fig. 8 shows my device in use on a person.

As here embodied my improved swimming garment comprises two pieces of material 10 and 11 formed and cut so as to provide a waist or undergarment such as a girdle or present-day corset, adapted to encircle the waist of the wearer, under the arms. The said members 10 and 11 are secured together at the edges thereof, as at 12, by a strip of any desired suitable material preferably vulcanized to the said members 10 and 11, so as to provide a semi-airtight garment. Eyelets 13 and 14 are secured to the edges of the members 10 and 11, positioned at the rear of the said garment, adapted to receive the usual lace 15, tape, string, or the like, secured or tied, as at 16, to the extremities so as to permit the garment to be securely held in position on the body of the wearer.

Tapes 17 and 18 are secured at their extremities, as at 19, 20 and 21, 22, respectively, by eyelets similar to the hereinbefore described eyelets, to the upper portion of the said garment, and extended upwardly therefrom, adapted to extend over the

shoulders of the wearer. Similar tapes 23 and 24 are secured at their extremities, as at 25, 26, and 27, 28, respectively, by eyelets similar to the hereinbefore described eyelets, to the lower portion of the said garment and extended downwardly therefrom, adapted to extend between the limbs of the said wearer. The latter described construction is such as will securely hold the said garment in place on the body of the wearer.

The above described garment is provided with a front central extended portion 29, having secured thereto a ring member 30, over which the tubular member 31 is engaged. The said tubular member 31 is provided with a threaded aperture adapted to receive the extended member 32 of hollow construction, and provided with an enlarged upper portion 33, adapted to be placed over the mouth of the wearer of my improved garment. The said enlarged upper portion 33 is provided with lug elements 34 and 35, adapted to be gripped by the teeth of the wearer. The valve 36 is freely mounted in the tubular member 32 and is held therein by rods 37 and 38, extended across the opening formed in the said tubular member and secured thereto. The valve 36 is constructed so as to permit air to be forced by the wearer of my improved garment into the said garment, so as to prevent the escape of the air. It should be understood that the above described construction is such as will permit my improved garment to be maintained in an inflated condition while the wearer is swimming or floating in the water.

I have also shown a plurality of eyelets 39 similar to the hereinbefore mentioned eyelets, secured to my improved garment, and positioned or arranged in vertical rows, preferably staggered so as to provide reinforcement for the said garment, and so as to provide a better fitting garment, conforming more closely to the body of the wearer.

In Fig. 3 of the accompanying drawing, I have shown my improved garment provided with an extended portion 29', comparatively shorter than the above mentioned and described extended portion 29. The tubular member 40 is secured thereto, and extended therefrom and has secured thereto, at its extended extremity, a valve housing 41, having freely mounted therein the usual valve so as to permit air to be blown into my improved garment, and so as to prevent

the escape of the said air therefrom. It should be understood that my improved garment when equipped with the above mentioned valve will be constructed by some-
5 what heavier material suitably treated so as to be air tight and preferably inflated before applied or placed in position on the wearer.

In Fig. 4 of the accompanying drawing, 10 I have shown the method of attaching the hereinbefore mentioned eyelets to my improved garment, and which comprise the usual tubular member 42, having a flanged portion 43 or rim and which is inserted 15 through apertures formed in the said members 10 and 11, reinforcing members 44 and 45 of ring shaped construction being placed adjacent to the members 10 and 11, and the flanged portion 43 and the eyelet ring 46, the 20 extremity of the tubular member 42 being crimped or bent outwardly and downwardly, against the eyelet ring 46 so as to securely hold the said eyelet in place and so as to prevent the escape of air from my improved 25 garment.

In Fig. 5 of the accompanying drawing, I have shown a disc member 48, preferably of soft material sewn or stitched as at 49, to the ring member 44, so as to prevent the flanged 30 portion 43 of the said tubular member 42 from chafing or irritating the skin of the wearer.

In Fig. 6 of the accompanying drawing, I have shown a disc member 50 of similar ma- 35 terial to the above mentioned disc member 48, for a similar purpose adapted to enclose or cover the flanged portion 43 of the tubular member 42 and provided with extended portions 51 adapted to engage under the said 40 flanged portion 43, so as to securely hold the said disc member 50 in place.

In Fig. 7 of the accompanying drawing, I have shown a disc member 52, having

formed therein a central aperture, adapted to receive the tubular member 42. The said disc member 52 is gathered around and over the flanged portion 43 and stitched or sewn as at 53, and forced into the central opening of the said tubular member 42, so as to provide a smooth outer surface for the purpose 50 as above set forth.

In Fig. 8 my device is shown to be in use and lacing 15 is shown to be attached to the front of the garment.

Having thus described my invention, what 55 I claim as new and desire to protect by Letters Patent of the United States is as follows:

1. In a device of the class described, two pieces of material formed to provide a garment, a strip secured along the edges of the said pieces for joining the pieces to provide an air chamber, and a plurality of eyelets engaged thru the said pieces for preventing excessive inflation of the air chamber 60 by holding the said pieces together for providing a neat fitting garment.

2. In a device of the class described, two pieces of material formed to provide a garment, a strip secured along the edges of the 70 said pieces for joining the pieces to provide an air chamber, and a plurality of eyelets engaged thru the said pieces for preventing excessive inflation of the air chamber by holding the said pieces together for providing a neat fitting garment, and cloth disc members engaged under the heads of the eyelets, and cross the faces of the eyelets, excess material from the said cloth discs being forced into the hollow portions of the 75 eyelets, for preventing the eyelets from directly engaging against a wearer.

In testimony whereof I have affixed my signature.

SIMON BRYGIDER.
